UNITED STATES PATENT OFFICE.

HOBART O. CLARKE, OF PITTSBURG, AND ARTHUR G. ROSS, OF WILKINSBURG, PENNSYLVANIA.

HANGING STAGING-HOIST.

No. 853,161.

Specification of Letters Patent.

Patented May 7, 1907.

Application filed October 16, 1906. Serial No. 339,168.

To all whom it may concern:

Be it known that we, HOBART O. CLARKE, a resident of Pittsburgh, in the county of Allegheny and State of Pennsylvania, and ARTHUR G. Ross, a resident of Wilkinsburg, in the county of Allegheny and State of Pennsylvania, both citizens of the United States, have invented a new and Improved Hanging Staging-Hoist, of which the following is a full, clear, and exact description.

This invention is an improved staging hoist adapted to be suspended at the side of a building and used by brick masons, painters and others during the building operation.

The primary object of the invention is the production of a device of this character, capable of easy, vertical adjustment, especially avoiding complicated and expensive mechanism or such as would interfere with the free movement of the workman on the stage or platform.

With this and other objects in view, one embodiment of the invention consists of a plurality of depending bars supported by suitable outriggers, the bars having a number of apertures to be engaged by pins or the like to sustain the stage therefrom. A drum adjustably carried by each of the bars is operable by a lever and ratchet mechanism to elevate or lower the stage, through an intermediate flexible connection, to the required elevation.

Reference is to be had to the accompanying drawings forming a part of this specification, in which similar characters of reference indicate corresponding parts in all the figures.

Figure 1 is a perspective view of a plurality of our improved staging hoists as applied to the side of an unfinished building, and Fig. 2 is a side elevation of one hoist, partly in section at one side.

1 indicates an overhanging beam or outrigger, which is ordinarily supported from the framework of a building during the building operation, as shown in Fig. 1. Several of these beams are provided, which are arranged in pairs in slightly separated relation and are connected together by transverse bolts or other suitable devices. Between each pair of outriggers pass two depending bars 2, which are adjustably supported therefrom by bolts 3 passing through any one of a number

of equidistant apertures 4 arranged on the longitudinal center of each bar. Guided on each bar 2 below the outrigger 1 are cross-beams 5 arranged in pairs, embracing a pair of bars and connected together by bolts 6.

Supported on any number of pairs of cross-beams 5, preferably 3, is a stage or platform 7, having a vertical back-board 8 positioned against the outer bars 2 for preventing material from dropping from the platform into the street. The platform of each hoist is sustained in adjusted position from the bars 2 by means of bolts 9 passing through the apertures 4 of the bars at the same elevation and below the crossbeams 5, the latter resting on the bolts when the bolts are in position.

For adjusting the vertical height of the stage or platform 7 is provided a cross-shaft 10 for each pair of bars, journaled near each end in brackets 11 and 11^a, said brackets being adjustably connected to the bars by hooks 12 passing through the apertures 4 at the same elevation. Each shaft 10 has fixed to it adjacent to the bracket 11^a, a ratchet-wheel 13, which is normally engaged by a gravity pawl 14 pivoted on a stud or pin carried by said bracket. Each ratchet-wheel is further engaged when in operation, by a pawl 15 pivoted between the forked end of an operating lever 16, the forked end of said lever being journaled on the shaft 10 at each side of the ratchet-wheel 13. It is apparent from this construction that on oscillating the levers 16 the pawls 15 will engage the ratchet-wheels and turn the shafts 10, which will be prevented from turning in the opposite direction by the pawls 14.

Fixed to the outer ends of the shafts 10 are drums 17 having wound thereabout ropes or other flexible connections 18, which are provided with loops 19 at their free ends, passing over the ends of the cross-beams 5, each rope embracing a pair of said beams. The drums 17 are preferably splined to the shafts 10 in order that they may be longitudinally adjusted thereon to decrease or increase the width of the stage in accordance with the character of the work in which it is used.

In the operation of the hoist, the levers 16 are simultaneously oscillated to adjust the stage or platform at the required elevation, after which the bolts 9 are passed through

apertures in the bars adjacent to the under face of the cross-beams 5. The levers 16 are then moved in order that the pawls 14 may be released to lower the platform so that the cross-beams may rest on the bolts.

5 We have described the preferred form of the invention in order that the construction and operation might be fully understood. We, however, regard the precise construction as not material and consider the invention limited by the scope of the annexed claims only.

Having thus described our invention we claim as new and desire to secure by Letters 15 Patent:

1. In a staging hoist, in combination, depending bars adapted to be supported from overhanging beams or outriggers, a platform guided on said bars and adapted to be sustained therefrom, means carried by the bars operable to elevate the platform, and means providing for the vertical adjustment of the elevating means.

2. In a staging hoist, in combination, depending bars supported from suitable outriggers, a platform guided on said bars and adapted to be sustained therefrom, and means carried by the bars operable to elevate the platform.

3. In a staging hoist, in combination, outriggers, a platform, bars depending from the outriggers and arranged at opposite sides of the platform, means for guiding the platform on the bars, means for supporting the platform on the bars, and independent means carried by the bars for moving the platform in a vertical direction.

4. In a staging hoist, in combination, a platform, supports, a plurality of bars depending from said supports and arranged at each side of the platform on which the latter is guided, a cross shaft supported from a pair of said bars, a drum fixed to each end of the cross shaft, flexible connections between the drum and platform, and means for revolving

the cross shaft for adjusting the vertical height of the platform.

5. In a staging hoist, in combination, outriggers, a plurality of pairs of bars depending from the outriggers, a stage guided on said bars, a shaft journaled in bearings carried by each of said bars, a drum fixed to each shaft, flexible lines connecting the drums with the stage, and means for rotating said shafts to adjust the vertical height of the stage. 55

6. In a staging hoist, in combination, supports, perforated bars depending from said supports, a stage guided on said bars below the supports, a cross shaft journaled in bearings on each pair of bars, means for adjustably suspending the bearings from the apertures in the bars, drums fixed to said cross-shafts, and means connecting the drums with the stage for adjusting its vertical height 60 on the bars. 65

7. In a staging hoist, in combination, supports, a plurality of bars depending from said supports, each bar being provided with a series of apertures, a stage guided on said bars, means adapted to engage certain of 70 said apertures for sustaining the stage from the bars, and means in engagement with other of said apertures for vertically adjusting the stage.

8. In a staging hoist, in combination, supports, a pair of bars depending from said supports, a pair of cross-beams embracing and guided on said bars, a platform carried on said cross-beams, a shaft having a drum at each end carried by the bars, and flexible 80 connections attached to the drums and looped about the cross-beams. 75

In testimony whereof we have signed our names to this specification in the presence of two subscribing witnesses.

HOBART O. CLARKE.
ARTHUR G. ROSS.
